(57) **CLAIM**

The ornamental design for safety elastic rope, as shown and described.

DESCRIPTION

FIG. 1 is a perspective view of safety elastic rope showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is another perspective view of the safety elastic rope in use.

The safety elastic rope is shown broken apart for ease of illustration and indicates that no specific length is claimed. The broken lines shown in the drawings represent environmental structure and form no part of the claimed design.
